UNITED STATES PATENT OFFICE

105,558

DESIGN FOR A DRESS

Albert Ruchman, New York, N. Y.

Application June 15, 1937, Serial No. 69,846

Term of patent 3½ years

To all whom it may concern:

Be it known that I, Albert Ruchman, a citizen of the United States of America, residing in Manhattan, county of New York, and State of New York, have invented a new, original, and ornamental Design for a Dress, of which the following is a specification, reference being had to the accompanying drawing, forming part thereof, wherein,

Figure 1 is a front view of a dress showing my new design.

Figure 2 is a rear view of the dress shown in Figure 1.

The characteristic feature of my design resides in the combination on the net coat type dress, as shown, of the rows of ric-rac trimming around the collar and sleeve and along each side of the front opening as shown.

I claim:

The ornamental design for a dress, substantially as shown, and described.

ALBERT RUCHMAN.
